US00D670293S

(12) **United States Design Patent**
Shimizu et al.

(10) **Patent No.:** US D670,293 S
(45) **Date of Patent:** ** Nov. 6, 2012

(54) **DIGITAL READER COVER**

(75) Inventors: **Naoto Shimizu**, San Diego, CA (US); **Keiichi Totsuka**, Rolling Hills Estates, CA (US); **Isamu Arie**, Carlsbad, CA (US); **Yasushi Ezure**, San Diego, CA (US); **Takayuki Kitahara**, San Diego, CA (US); **Junghee Yeo**, San Diego, CA (US); **Nachi Watanabe**, Tokyo (JP); **Satoshi Aoyagi**, Tokyo (JP)

(73) Assignee: **Sony Corporation**, Tokyo (JP)

(**) Term: **14 Years**

(21) Appl. No.: **29/393,030**

(22) Filed: **May 27, 2011**

(51) LOC (9) Cl. **14-02**

(52) U.S. Cl. **D14/440**

(58) **Field of Classification Search** D14/250, D14/251, 253, 240, 217, 496, 440, 203.3, D14/203.4, 203.5, 203.8, 432, 439, 300; D3/218, 215, 201; 220/4.02; 248/309.1; 361/679.56, 679.03; 379/426, 433.11, 455; 455/575.1, 575.8; 190/100; 206/305, 320

See application file for complete search history.

(57) **CLAIM**

The ornamental design for a digital reader cover, as shown and described.

DESCRIPTION

FIG. 1 is a perspective view of the invention illustrating the top surface.

FIG. 2 is a top plan of the invention.

FIG. 3 is a bottom plan of the invention.

FIG. 4 is a side elevational view of the invention.

FIG. 5 is side elevational view of the invention opposed to the side illustrated in FIG. 4.

FIG. 6 is an end elevational view of the invention.

FIG. 7 is an end elevational view of the invention opposed to the end illustrated in FIG. 6.

FIG. 8 is a perspective view of the invention illustrating the bottom surface.

FIG. 9 is a perspective view of the invention in an open position and having dashed lines representing part of the digital reader which is to be held by the invention.

FIG. 10 is a perspective view of the invention in an open position; and,

FIG. 11 is a side elevational view of the invention in an open position.
